UNITED STATES PATENT OFFICE

140,379

DESIGN FOR A COMBINED RADIO AND PHONOGRAPH CABINET

Adolph D. Lambach, Chicago, Ill.

Application May 13, 1944, Serial No. 113,579

Term of patent 14 years

(Cl. 56—4)

To all whom it may concern:

Be it known that I, Adolph D. Lambach, a citizen of the United States and a resident of Chicago, in the county of Cook and State of Illinois, have invented a new, original, and ornamental Design for a Combined Radio and Phonograph Cabinet, of which the following is a specification, reference being had to the accompanying drawings, forming a part thereof.

Fig. 1 is a front perspective view of the combined radio and phonograph cabinet showing my new design;

Fig. 2 is a view similar to Fig. 1 showing the record player compartment partly open.

Fig. 3 is a similar view showing the record player compartment completely open; and

Fig. 4 is a top plan view of the cabinet with the record player compartment closed.

The other side of the cabinet as shown in the figures is substantially the same as the side shown and the back is without embellishment.

I claim:

The ornamental design for a combined radio and phonograph cabinet, substantially as shown and described.

ADOLPH D. LAMBACH.
